FIG. 1

FIG. 3

Alfred J. Bratton

WITNESS:

Abraham Atlas

INVENTOR

BY *Victor J. Evans*

ATTORNEY

UNITED STATES PATENT OFFICE.

ABRAHAM ATLAS, OF PHILADELPHIA, PENNSYLVANIA.

REPRODUCER.

1,395,937.

Specification of Letters Patent.

Patented Nov. 1, 1921.

Application filed June 19, 1920. Serial No. 390,241.

To all whom it may concern:

Be it known that I, ABRAHAM ATLAS, a citizen of the United States, residing at Philadelphia, in the county of Philadelphia and State of Pennsylvania, have invented 5 new and useful Improvements in Reproducers, of which the following is a specification.

The invention relates to phonographs and 10 more particularly to the reproducers therefor, and has for an object to provide a reproducer for reproducing vocal, instrumental or other sounds.

Among other features the invention comprehends a reproducer, designed to be cheaply manufactured and effectively produce sounds from the grooves or sound undulations of a phonograph record and to this end use is made of a body preferably 20 carried on a suitable swinging support so that it can operate over the record and with the aid of a stylus produce the sound simulating the nature of the particular sound record from the same by instrumental or 25 vocal production, the usual amplifier or horn being dispensed with.

In the further disclosure of the invention reference is to be had to the accompanying drawings constituting a part of this specification, in which similar characters of reference denote corresponding parts in all the views, and in which,—

Figure 1 is a fragmentary side elevation showing the application of the reproducer.

Fig. 2 is a vertical longitudinal sectional view taken through the reproducer substantially on the line 2—2 in Fig. 1, and

Fig. 3 is a horizontal sectional view taken through the reproducer.

Referring more particularly to the views a phonograph 10 consisting substantially of the usual cabinet 11 in which is disposed a motor (not shown), connected with a spindle 12 for rotating a turn table 13 includes also

an upright 14 on which is disposed a horizontally swinging arm 15 in the nature of a support, the connection of the arm 15 with the upright 14 being such that a slight vertical movement of the arm can be obtained.

The usual phonograph record 16 is disposed to rotate with the turn table as shown and carried on the free end of the arm is the reproducer 17. The reproducer consists substantially of a solid body 18 formed preferably in a single casting to provide an annular flange 19 and a medial comparatively

thin disk or wall 20 in the nature of a diaphragm having a central cross opening 21 therein. Formed with the annular flange 19 is a socket 22 for the reception of a needle 60 or stylus 23 suitably held by a screw 24 threaded into the socket 22.

In use the support or arm 15 is swung to bring the stylus 23 into engagement with the grooves of the rotating record on the rotating turn table 13 and by reason of the peculiar nature and formation of the reproducer the desired sounds will be reproduced and will be sufficiently clear and loud to be easily distinguished and understood, the usual horn 70 or amplifier generally employed in connection with phonographs, being entirely dispensed with. It has been found in actual practice that the provision of the cross opening 21 in the diaphragm 20 and the particular relatively thin formation of the latter results in the production of sound of surprising clearness and loud tone and it will be readily seen that the simple construction of the reproducer and the very 80 few parts comprehended in its make-up provide one which can be very cheaply manufactured and when combined with an instrument embodying merely a support, a turn table and a motor arranged in the cabinet 85 for operating the turn table, permits of constructing an instrument at a minimum cost because among other reasons the usual delicately constructed amplifier or horn is entirely eliminated.

Having described my invention, I claim—

1. A talking machine reproducer comprising an integral body of circular shape and formed relatively thick with its central portion considerably reduced in thickness 95 whereby to define a diaphragm, said diaphragm being formed with a central hole, and a socket member formed at a point in the periphery of said body and adapted to hold a stylus.

2. A talking machine reproducer comprising an integral body of circular shape and formed relatively thick with its central portion considerably reduced in thickness 105 whereby to define a diaphragm, said diaphragm being formed with a central hole, a socket member formed at a point in the periphery of said body and adapted to hold a stylus, said hole being tapered inwardly from both sides of the diaphragm.

In testimony whereof I affix my signature.

ABRAHAM ATLAS.
